UNITED STATES PATENT OFFICE

168,673

HAIRBRUSH OR THE LIKE

Leslie A. Carpenter, Palmer, Mass., assignor to Better Brushes, Incorporated, Palmer, Mass., a corporation of Massachusetts

Application March 24, 1951, Serial No. 14,611

Term of patent 14 years

(Cl. D9—2)

To all whom it may concern:

Be it known that I, Leslie A. Carpenter, a citizen of the United States residing at Palmer, Commonwealth of Massachusetts, have invented a new, original, and ornamental Design for a Hair Brush or the like, of which the following is a specification, reference being had to the accompanying drawing, forming a part thereof.

Referring to the drawing:

Fig. 1 is a side view of a hair brush or the like embodying my new design;

Fig. 2 is a top and bottom view;

Fig. 3 is an exploded view in perspective with the separable brush element broken away for convenience of illustration, and

Fig. 4 is a sectional view on line 4—4 of Fig. 1 of the same.

The essential features of my design reside in those portions indicated by solid lines.

I claim:

The ornamental design for a hair brush or the like, as shown and described.

LESLIE A. CARPENTER.
